DESIGN FOR AN EDUCATIONAL DEVICE

John V. Horr, North Tarrytown, N. Y., assignor
to Einson-Freeman Co., Inc., Long Island City,
N. Y., a corporation of Delaware

Application March 28, 1944, Serial No. 113,056

Term of patent 14 years

(Cl. D25—1)

To all whom it may concern:

Be it known that I, John V. Horr, a citizen
of the United States and a resident of North
Tarrytown, county of Westchester, and State of
New York, have invented a new, original, and
ornamental Design for an Educational Device,
of which the following is a specification, reference
being had to the accompanying drawing, forming
part thereof.

Figure 1 is a front view of an educational device
embodying my new design;

Figure 2 is a rear view of the same; and
Figure 3 is a top edge view.

I claim:

The ornamental design for an educational de-
vice, substantially as shown.

JOHN V. HORR.
